J. J. O'CONNELL,
 ENVELOP REGISTERING MECHANISM FOR ENVELOP MACHINES,
 APPLICATION FILED AUG. 19, 1915.
1,196,018. Patented Aug. 29, 1916.

UNITED STATES PATENT OFFICE.

JOHN J. O'CONNELL, OF DAYTON, OHIO, ASSIGNOR TO MERCANTILE CORPORATION, OF DAYTON, OHIO, A CORPORATION OF NEW YORK.

ENVELOP-REGISTERING MECHANISM FOR ENVELOP-MACHINES.

1,196,018.

Specification of Letters Patent. Patented Aug. 29, 1916.

Application filed August 19, 1915. Serial No. 46,230.

To all whom it may concern:

Be it known that I, JOHN J. O'CONNELL, a citizen of the United States, residing at Dayton, Montgomery county, and State of Ohio, have invented certain new and useful Improvements in Envelop-Registering Mechanism for Envelop-Machines, of which the following is a full, clear, and exact description.

- 5 10 This invention relates to certain new and useful improvements in machines for making envelopes and is particularly adapted for use in continuous rotary machines in which, a series of envelop blanks are fed through 15 the machine and fabricated by means of folding, gumming and printing operations into a complete envelop. In such machines it is important that the register of the blank or partially completed envelop be correct before certain further operations are performed. This correct register is necessary 20 in order that the printing and gumming operations be performed on the proper place on the envelop. To obtain exact register I have 25 found that a certain arrangement of register pins and rollers will correctly aline each envelop and allow it to feed forward at the proper time to subsequent devices such as gummers or printers.
- 30 In the drawing Figure 1 shows an end view of the register rolls and register pins and also shows the path of an envelop as it approaches and leaves the registering devices. Fig. 2 shows a top plan view of the 35 register roll and register pins with an envelop in position on the pins. Fig. 3 shows a detail view of the cam mechanism to operate the register pins. Fig. 4 shows another detail view of the cam mechanism 40 shown in Fig. 3 with the parts in a different position.

In Fig. 1 the envelop advances from preceding mechanism along line 10 in the direction of the arrow. It eventually enters the 45 bight of envelop feeding rolls 11 and 12 and is delivered from these rolls in proper register and at the proper time to subsequent mechanism. The envelop leaving the rolls advances in a path tangential to the 50 rolls as along the line 13.

In Fig. 2 the dotted lines 14 and 15 show the forward edge of the envelop and indicate the position that the envelop may have assumed in advancing to the rolls 11 and 12.

55 This figure also shows an envelop 16 in the

proper position to enter the bight of the rolls. In order to position the envelop from the received position *i. e.*, 14 or 15 to correct position 16, I employ register pins 17 and 18. These pins project outwardly a considerable 60 distance from the periphery of roll 12 and are adapted to engage the envelop and allow it to settle to proper position before passing into the bight of rolls 11 and 12. To insure the envelop settling correctly and to exactly 65 time the advancing of the envelop into the bight of the rolls 11 and 12 I employ certain mechanism which will now be described.

The register pins 17 and 18 are secured to a shaft 19 and project outwardly therefrom 70 through slots 20 in rollers 12. The shaft 19 extends through roller 12 to the right and through a hollow shaft 21 which forms one supporting shaft for the roller 12. Hollow shaft 21 is journaled in a boss in a side frame 22 of the machine. Shaft 23 projects from the opposite side of roller 12 and is similarly journaled in a boss in side frame 22. This shaft projects beyond the side frame and carries a gear or other driving 75 device (not shown) for turning the shafts 21 and 23 and roller 12. In order to provide clearance for the points of pins 17 and 18 so that they may pass roller 11 this roller is cut away as shown at 24. See Fig. 1. 80 Roller 11 is supported on a shaft 40 which is journaled in the side frames 22 and driven by gearing (not shown) or other driving mechanism at the same speed as roller 12. The register pins 17 and 18 normally rotate 85 in unison with roller 12. Just before the envelop reaches the bight of rolls 11 and 12 these pins are given a rearward movement 90 with respect to advancing rotation of rolls 12. This gives the envelop time to settle 95 into proper alinement on the register pins and accurately times the gripping of the envelop between the rolls 11 and 12. After the envelop passes into the bight of rolls 11 and 12 the pins 17 and 18 are advanced relatively to roll 12. This advancing movement of the pins removes them to a position in which they will not interfere with the advancing front edge of the envelop as it emerges from the rolls 11 and 12.

To impart the above mentioned relative movement to the pins I employ the following mechanism: The hollow shaft 21 is extended through the boss on the side frame 22 and carries on its outer end an arm 25. 105 110

A short shaft 26 is pivotally mounted in this arm and this shaft carries on one end the arm 27 and on the other the arm 28. Arm 26 carries a stud 29 which supports a cam 5 roller 30 which co-operates with the register pin operating cam 31 which is fixed to the boss on the side frame 22 of the machine. A side view of this cam is shown in Figs. 3 and 4 and it will be seen that it has a gradually increasing throw at 32 and that beyond the peak of the cam the cam surface falls in straight line 33 which has the effect of causing a gradual lift and a quick return of the cam follower roller 30. On the rotation of hollow shaft 21 arm 25 carries the shaft 26, arm 27, stud 29 and roller follower 30 around the fixed cam and the fixed cam imparts a rocking movement to the shaft 26.

The shaft 19, which carries the register pins, extends through the hollow shaft 21 fixed cam 31 and arm 25 and carries on its end a bifurcated arm 34. Engaging the slot in said bifurcated arm is a roller 35 which is carried on a stud 36 which projects inwardly from the arm 28 carried on shaft 26. In order to hold the register pins 17 and 18 in forward position in the slots 20 and to hold the roller follower 30 in contact with the fixed cam 31 I employ a tension spring 30 37 which is secured to a post 38 attached to arm 34 on shaft 19. The opposite end of this spring is attached to a post 39 which is attached to the arm 25 on hollow shaft 21.

The operation of the device is as follows: 35 The envelop advances along the line 10 (Fig. 1) and eventually contacts with the register pins 17 and 18 which are in the position shown in Figs. 1 and 3. These pins arrest the envelop and just before the envelop 40 reaches the bight of the rolls 11 and 12 the register pins are given a slight relative rearward movement by fixed cam 31. The follower 30 rides up on the side 32 of cam 30 and thereby rocks shaft 26 and through arm 45 28, stud 36 and roller 35, rocks the bifurcated arm 34 in a clockwise direction. Bifurcated arm 34 being attached to shaft 18 moves the register pins 17 and 18 in a clockwise direction in slot 20 and thereby aligns 50 the envelop properly. The position of parts when the pins 17 and 18 are in rocked position is shown in Fig. 4. The envelop then passes into the bight of rolls 11 and 12 at a definite time period since the pins 17 and 55 18 have caused the envelop to be advanced into the rolls at the exact time the rear edge of the pins passes the line of centers of rolls 11 and 12. The pins pass into the cut away parts 24 of roll 11 and shortly after they 60 pass the line of centers of rolls 11 and 12 the follower 20 rides down the abrupt face of cam 31. The follower being drawn to contact with the cam by means of the spring 37. This serves to rock shaft 19 in a counter-clockwise direction and restores the pins

17 and 18 to their normal position in the forward portion of slots 20. When the pins are in this position (shown in Fig. 3) the envelop can emerge from rolls 11 and 12 in a path which is substantially tangential to the periphery of the cylinders or rolls, (see Fig. 1) and can travel forward in this path without contacting with the pins and when delivered to the subsequent mechanism its registry and timing will be correct. 75

It is to be understood that I do not limit myself to the precise form and construction shown in the drawings and described in the specification.

What I claim as my invention is particularly pointed out in the appended claims. 80

I claim:—

1. In a device of the class described, a pair of envelop feeding rolls in contact with one another and adapted to grip an envelop 85 passing therebetween by the engagement of the rolls with the opposite sides of the envelop, a shaft axially aligned with the axis of one of the rolls and adapted to rotate with said roll, a pair of pins secured to said 90 shaft and projecting through slots in the roll, means for imparting a relative rearward rotation of said shaft and pins with respect to said roll as the pins approach the bight of the rolls to register an approaching 95 envelop and means for imparting a relative forward rotation of said shaft and pins with respect to the roll in which the shaft is mounted when the envelop is gripped between the pair of rolls whereby the pins are 100 displaced from the path of the emerging envelop and whereby the envelop is permitted to advance without interference.

2. In a device of the class described, a plurality of envelop feeding rolls, in combination with means for registering an envelop as it approaches the bight of said rolls comprising a pair of pins carried by a shaft in axial alignment with the axis of one of said rolls and normally rotating in unison 105 with said rolls and means for retarding the rotation of said pins as they approach the bight of said rolls and for accelerating the rotation of said pins as they move away from the bight of said rolls. 115

3. In a device of the class described, in combination, a plurality of envelop feeding rolls, a plurality of register pins projecting through slots in one of said rolls and normally rotating in unison therewith, said pins projecting beyond the periphery of the roll with which they rotate in unison and extending into recesses in the co-operating rolls and means for retarding the rotating movement of the pins to cause a relative 120 movement between the periphery of one of said rolls and the pins whereby an envelop approaching the feed rolls is accurately registered. 125

4. In a device of the class described, a pair 130

- of envelop feeding rolls, in combination with a pair of register pins projecting through slots in one of said rolls, a shaft within and axially alined with the axis of 40
 6 one of said rolls, to carry the aforesaid pins, and cam means associated with said shaft to rock the said shaft and the pins thereon and thereby register an envelop as it approaches the envelop feeding rolls.
- 10 5. In a device of the class described, in combination, a pair of envelop feeding rolls, a shaft concentrically journaled in one of said rolls, a pair of pins attached thereto and projecting through slots in the roll to 45
 15 a point beyond the periphery thereof, means for normally maintaining the pins in the forward position of said slots, and means operable by the rotation of the rolls for retracting the pins rearward in said slots 50
 20 thereby causing a relative movement of the pins and the periphery of the rolls and thereby registering an envelop as it approaches the rolls.
6. In a device of the class described, a pair 55
 25 of envelop feeding rolls, a member concentric with and rotating in unison with said rolls, a plurality of register pins projecting through slots in one of said rolls and carried by said member, and cam means operable by 60
 30 the rotation of the rolls to rock said member and the pins thereon in a direction opposite to the direction of the rotation of the said rolls, and thereby register an envelop as 65
 35 it approaches said feeding rolls, and means associated with said cam means to rock said member and the pins thereon in the opposite direction when the envelop is engaged by the feeding rolls whereby the pins are displaced from the substantially tangentially envelop path whereby the envelop may be advanced along said path by the feeding rolls without interference.

In testimony whereof I affix my signature in the presence of two subscribing witnesses.

JOHN J. O'CONNELL.
